UNITED STATES PATENT OFFICE.

JOHN E. AMERMAN, OF BROOKLYN, NEW YORK.

GAS-ENGINE IGNITER.

1,162,206.

Specification of Letters Patent. Patented Nov. 30, 1915.

Application filed February 20, 1915. Serial No. 9,692.

To all whom it may concern:

Be it known that I, JOHN E. AMERMAN, a citizen of the United States, residing at Brooklyn, in the county of Kings and State of New York, have invented new and useful Improvements in Gas-Engine Igniters, of which the following is a specification.

This invention relates to igniting devices for explosive engines and it consists in the novel features hereinafter described and claimed.

An object of the invention is to provide an attachment adapted to be applied to the cylinder of an explosion engine having means for permitting the explosive gases to enter the attachment as the gases are compressed by the movement of the piston in the cylinder. Also means is provided for regulating the flow of gas from the cylinder into the attachment whereby the gas may be permitted to pass from the cylinder into the attachment in a stream of desired diameter. A catalytic substance as for instance platinum sponge or aluminum is held within the attachment and when the gas contacts with the same it is ignited. When the piston begins to move away from that end of the cylinder at which the attachment is applied the flame is drawn into the cylinder and the body of compressed gas contained therein is exploded and thus the force or momentum incident to the explosion is applied to the piston and accelerates its movement away from that end of the cylinder at which the attachment is mounted. The said attachment is made globular in form in order that it may the more readily withstand the sudden pressure and forces to which it is subjected when the explosion takes place.

In the accompanying drawing the figure is a sectional view of the end portion of the cylinder of an explosive engine showing the attachment applied thereto and in section.

The cylinder 1 to which the attachment is applied is of the usual form employed in explosive engines and a piston 2 is movably mounted therein in the usual manner. The cylinder 1 is provided at its end with an opening 3 through which a spark plug is usually passed. In the present invention the spark plug is removed from the cylinder and the attachment hereinafter described is inserted in the opening 3.

The attachment comprises a nipple 4 which is screwed in the opening 3 and the

transverse sectional area of the passage-way through the nipple 4 is regulated or controlled by a valve 5 turnably mounted in the said nipple. A hemispherical portion 6 is formed at the upper end of the nipple 4 and a hemispherical member 7 is screw-serted into engagement with the upper portion of the part 6 there being a gasket 8 of any suitable material interposed between the meeting edges of the portion 6 and the member 7 as best shown in the drawing.

A stem 9 is screw-serted in the center of the member 7 and at the upper portion thereof and carries at its lower end a cup 10 which retains a catalytic substance 11 as for instance platinum sponge or aluminum. When the member 7 is applied to the portion 6 they combine to form a globular body in order to withstand the strain to which the body is subjected when the gas is exploded.

The operation of the device is as follows. Assuming that the piston is moving away from the nipple 4 upon its intake stroke the gas is admitted in the cylinder 1 in the usual manner and when the piston 2 begins to move toward the nipple 4 upon the compression stroke the gas is forced through the nipple 4 and past the valve 5 into the interior of the portion 6 and the member 7. When the gas comes in contact with the catalytic substance 11 it is ignited but the flame remains in the portion 6 and the member 7 so long as the piston 2 is moving toward the nipple 4. When the piston 2 arrives at the end of its stroke toward the nipple 4 and begins to move away from the same the flame is drawn to the nipple 4 into the cylinder 1 and the compressed gas in the cylinder is exploded or ignited behind the piston 2 and the piston is accelerated in its movement away from the nipple 4.

By adjusting the valve 5 the transverse sectional area of the passage way for the gas through the nipple 4 may be regulated so that the gas may flow from the cylinder 1 into the portion 6 and member 7 in a comparatively fine stream or coarse stream as desired. Therefore it will be seen that an igniting device adapted to be applied to an explosion engine and of simple and durable structure is provided and that the device operates automatically to affect the explosion of the gas and at proper time with relation to the movement of the piston. Also means is provided for regulating the quan-

ity of gas which may be permitted to pass from the cylinder into the explosion chamber of the device.

Having described the invention what is 5 claimed is.—

An igniter adapted to be applied to an engine cylinder comprising a chamber, means for permitting gas to pass from the cylinder into the chamber, a stem supported

from the wall of the chamber, a cup carried 10 by the stem and a catalytic substance carried by the cup.

In testimony whereof I affix my signature in presence of two witnesses.

JOHN E. AMERMAN.
